UNITED STATES PATENT OFFICE.

CHARLES F. SCHULTIS, OF CLEVELAND, OHIO, ASSIGNEE TO CHRISTIAN GIRL, OF CLEVELAND, OHIO.

THREADING DEVICE.

1,135,057.

Specification of Letters Patent.

Patented Apr. 13, 1915.

Application filed December 8, 1910. Serial No. 596,199.

To all whom it may concern:

Be it known that I, CHARLES F. SCHULTIS, a citizen of the United States, residing at Cleveland, in the county of Cuyahoga and State of Ohio, have invented a certain new and useful Improvement in Threading Devices, of which the following is a full, clear, and exact description, reference being had to the accompanying drawings.

10 This invention relates to screw threading devices, and particularly to devices or tools of this class which embody dies for cutting threads and wherein the dies are adapted and constructed to open automatically.

15 One of the objects of this invention is to provide an improved construction whereby, when the work has been threaded a certain distance, the dies will be automatically opened, thereby obviating the necessity of reversing the rotation of the tool or of the work, to withdraw the latter.

20 A further object of the invention is to provide efficient means whereby, when the end of the thread is reached on the work, and it is impossible to advance the work on the tool, further rotation of the work or of the tool will not result in stripping the thread, but will cause the dies to automatically open and release the work.

25 A still further and general object of the invention is to provide a tool of the character set forth, which is simple and economical of production and efficient in operation.

30 I accomplish the foregoing objects by the construction illustrated in the drawings hereof, wherein—

35 Figure 1 represents a side elevation, with parts broken away, of a device constructed in accordance with my invention; Fig. 2 a front elevation of said device; Fig. 3 a side elevation of the device taken at about right angles to Fig. 1; Fig. 4 a central longitudinal section through said device; Fig. 5 a view similar to Fig. 4, showing the jaw levers opened by the movement of the abutment; Fig. 6 a similar view showing the jaw levers opened by the forward movement of the levers, and Fig. 7 a sectional view on the line 7—7 of Fig. 5.

40 The tool illustrated herein is a die stock which is adapted to be mounted either in a machine of the turret type, in which the tool is securely fixed while the work is fed there-

to, or in a machine in which the tool is rotated and moved endwise while the work is fixed, as in certain types of screw machines, or in a machine wherein the tool is rotated and the work is fed thereto.

45 Describing the parts by reference characters, 1 denotes the shank of the tool, said shank having a head 2 preferably integral therewith. The shank is provided with a central bore 3, said bore merging with an enlarged recess or chamber 4 in the vicinity 55 of the head of the tool and this recess in turn merging with a larger recess or chamber 5 formed within the head. This last recess or chamber may be square in section.

50 The head proper is provided with a central chamber 6, extending substantially the full length thereof, and with a pair of opposed recesses extending from the outer periphery thereof into and communicating with the chamber, said recesses forming 60 guide-ways for a pair of levers which carry the dies or chasers. These recesses are indicated at 7 and the levers referred to are indicated at 8 and are constructed and secured in place as follows: Each lever has 65 a front end thereof a recess extending outwardly from the inner face thereof, said recess being enlarged from front to rear by flaring the lateral sides thereof (as will appear from Fig. 1) to give it a dove-tailed 70 shape and adapt it to receive the correspondingly shaped die or chaser 9. To lock the dies or chasers in place, screws 10 are provided, each extending laterally through a jaw, through one of the flaring sides of 75 the recess and bearing against a die and, in order to adjust the dies, the screws 11 are provided, each extending through a jaw and bearing at its inner end against the outer portion of the die.

80 Each lever 8 is provided at its rear end with an inwardly projecting portion or flange 12 and the inner face of each lever is recessed, as shown at 13, the purpose of so reducing the thickness of the levers at this 85 point being not merely to reduce the weight of the same, but to afford a convenient means for compensating for the wear produced between the inner ends of the flanges 12 and a coöperating member, to be described hereinafter. Each of the levers is provided with a slit 14 extending forwardly 90 from the rear end thereof and providing a

relatively thin and flexible body 15 between said slit and the recessed portion 13, said body carrying the projection or flange 12. Each lever is provided with a threaded bore 5 extending from the outer surface inwardly to the slit 14 and in this bore there is mounted a screw-threaded stud 16, the stud being provided with notches 17 for the reception of a screw driver or similar adjusting means.

Each lever 8 is provided with a bore 18 extending rearwardly from the front face thereof and substantially parallel with the axis of the tool, the bore being located preferably at some point between the recess for the die 9 and the outer periphery of the lever. Each lever is provided with an elongated slot 19 extending through the same and intersecting the bore 18. In the rear 20 end of each bore 18 there is inserted a helical spring 20 and in front of this spring there is inserted a short rod 21, said rod being provided with a transverse bore. The levers 8 are pivotally connected to the head 2 by means of a pin 22 extending through the transverse bore provided in each rod and through the slot 19 in the lever, the pin having its outer end portions anchored in seats provided therefor in the head and 30 on opposite sides of each recess 7. These seats are conveniently formed by providing angular recesses 23 in opposite sides of the head 2 and by boring through the reduced portions 24 of the head thus provided, at 35 right angles to the bore 18. When the parts are in operating position, the pin extends through the front end of its slot 19 as shown in Fig. 4.

The head 2 is provided with a cylindrical 40 recess in its outer periphery adapted to receive a metallic ring 25, the outer surface of the ring being preferably flush with the rear surface of the head and the rear end of the ring abutting against a shoulder 26 45 formed on the head. For a purpose to be explained hereinafter, each stud 16 is drilled out to provide a recess 27 into which there is inserted a helical spring 28, the inner end of which bears against the bottom of the cup there formed and the outer end against the ring or shell 25.

Mounted within the bore 3 is a rod 29, which rod projects into the central chamber 6 in the head 2. On this rod there is 55 mounted an abutment 30, said abutment being adapted to slide within the chamber 5 and having notches 31 in opposite faces thereof. The abutment is secured to the rod by means of a set screw 32 in the head 60 2 and shell 25 and through a suitable bore provided in the abutment.

In the chamber 4 there is mounted a helical spring 34, one end of which bears against the rear of said chamber and at the 65 opposite end against the rear end of the

abutment. This spring will normally hold the abutment and the rod 29 in the position shown in Fig. 4, with the projections 12 bearing against the opposed faces of the abutment 30 and just at the rear of the notches 31. A helical spring 35 is mounted in the bore 3 and bears at one end against the rear end of the rod 29 and at its other end against an adjusting screw 36. The spring 35 forms a yielding resistance to the rearward adjustment of the rod 29 and will also assist the spring 34 in holding the rod and the abutment into normal or forward position.

The operation of the device is as follows: 80 The rod 29 will be set within the chamber 6 to the length of the thread to be cut upon the work. When the work engages the front end of the rod 29, whether the work be fed toward the tool or vice versa, the rod 29 will be thrust rearwardly against the action of the springs 34 and 35, carrying with it the abutment 30. As soon as the notches 31 are moved rearwardly a sufficient distance, the springs 28 will force the flanges 12 into said notches, rocking the levers 8 and disengaging the dies 9 from the work, as shown in Fig. 5. The work can then be withdrawn from the tool without the necessity of reversing the rotation of the tool or the work. When so withdrawn, the levers may be rocked on their pivots by merely grasping the projecting front ends of the same and pressing them toward each other. This will press the rear ends of the levers outwardly and allow the springs 34 and 35 to restore the rod 39 and abutment 30 to their normal position. The movement of the rod and abutment is permitted by the elongated slot 33, through which the screw 32 projects. Suppose the thread has been cut as far as possible on the work, further advance being prevented by the stop usually provided, further rotation of the work or the tool, as the case may be, will produce a 100 forward pull upon the levers 8, through the engagement of the die threads with the threads on the work. This pull will move the levers 8 forwardly, through the slots 19 on the pins 22, bringing the projections 12 105 into register with the notches 31, whereupon the springs 28 will force the inner ends of the levers inwardly and automatically separate the front or outer end of the levers, as shown in Fig. 6. The parts may be restored to normal position by pressing the front ends of the levers toward each other, thereby releasing the projections 12 from the notches 31. The springs 20 will 110 move the levers 8 rearwardly, through their engagement with the rear ends of the rods 21, which are rigidly pinned to the head 2. These springs normally hold the levers in their rearward position, with the pins 22 115 bearing against the front ends of the slots 130

19. As the abutting portions of the projections 12 and of the abutment 30 are liable to wear and thus produce a corresponding variation in the distance between the dies 9, this wear can be readily compensated for by threading the screws or plugs 16 inwardly into their respective bores and thereby forcing inwardly the projections 12, this result being made possible and convenient of accomplishment by the slits 14 and the reduction in thickness of the metal between said slits and the inner surfaces of the levers adjacent thereto.

Having thus described my invention, what I claim is:—

1. In a device of the character set forth, the combination of a shank, a slotted head carried by said shank and having a chamber therein, die-carrying levers pivotally mounted in the slots in said head, springs tending to force the rear ends of said levers inwardly, a rod slidably mounted in said shank and projecting into said chamber, an abutment adjustably mounted on said rod, and means yieldingly projecting said rod and abutment forwardly into said chamber, the abutment and the portions of said levers which are at the rear of their pivotal connection having coöperating abrupt portions adapted to be moved past each other when the abutment is moved rearwardly, so as to permit the abrupt inward movement of the rear ends of said levers.

2. In a device of the character set forth, the combination of die-carrying levers, means pivotally supporting said levers intermediate of their ends, springs forcing the rear ends of said levers inwardly, an abutment projecting between said levers and adjacent to the rear ends thereof, and a spring resisting the rearward movement of said abutment, there being a guideway for the abutment and said abutment being provided with abrupt notches for the rear ends of said levers and with supporting surfaces for such ends at the rear of said notches, and said levers having inwardly projecting end portions adapted to engage said surfaces and to enter said notches.

3. In a device of the character set forth, the combination of die-carrying levers, means pivotally supporting said levers intermediate of their ends, springs forcing the rear ends of said levers inwardly, an abutment projecting between said levers adjacent to the rear ends thereof and slidably mounted within a guide-way provided therefor, a spring resisting the rearward movement of said abutment, said abutment being provided with notches for the rear end portions of said levers and with supporting surfaces for such ends at the rear of said notches, and said levers having inwardly projecting portions adapted to engage said surfaces and enter said notches, and means

whereby the inwardly projecting end portions of the levers may be adjusted toward the abutment, independently of the bodies of the levers, to compensate for wear.

4. In a device of the character specified, the combination, with a supporting member, of die-carrying levers pivoted transversely thereof, means for permitting a limited longitudinal movement of said levers relative to said supporting members, dies carried by the front portions of said levers and means carried by said supporting member and movable relatively thereto for governing the position of said levers, said means and levers being so arranged that upon relative movement either caused by contact of the means with the end of the work or the forward movement of the dies along the thread of the work, the levers will swing upon their pivots and cause the dies to release the work.

5. In a device of the character specified, the combination of a pair of die-carrying members, supports therefor, a pivotal connection between each member and its support allowing said member to be moved forwardly with respect to said support, and means operating to automatically separate the die-carrying portions of said members when the latter are moved forwardly with respect to their supports.

6. In a device of the character specified, the combination of die-carrying members, supports therefor, means pivotally connecting said members and said supports, such pivotal connection allowing each member to move forwardly with respect to its support, means tending to move inwardly the portions of said members which are at the rear of their pivotal supports, and means normally preventing such inward movement.

7. In a device of the character specified, the combination of die-carrying members, supports therefor, each of said members having an elongated slot, a pin mounted in the support and extending through the slot and pivotally connecting each member to its support, a spring pressing each member rearwardly with respect to its support, means pressing inwardly the portions of said members which are located at the rear of their pivotal supports, and means normally preventing such inward movement.

8. In a device of the character specified, the combination of die-carrying members, each of said members having a longitudinal bore and provided with an elongated transverse slot extending therethrough and intersecting said bore, a spring in each bore at the rear of said slot, a movable abutment in each bore having its rear end operatively engaged by the spring therein, a support for each of said members, a pin mounted in each support and extending through said slot and said abutment, means forcing inwardly the portion of each member which is

at the rear of its pivotal connection with its support, and means normally preventing such inward movement.

9. In a device of the character specified, 5 the combination of die-carrying members, each of said members having a longitudinal bore and provided with an elongated transverse slot extending therethrough and intersecting said bore, a spring in each 10 bore at the rear of said slot, a movable abutment in each bore having its rear end operatively engaged by the spring therein, a support for each of said members, a pin mounted in each support 15 and extending through said slot and said

abutment, means forcing inwardly the portion of each member which is at the rear of its pivotal connection with its support, an abutment against which such rear portions of said members are adapted to bear, said 20 abutment having a supporting surface for each of said portions and being recessed in front of each such surface.

In testimony whereof, I hereunto affix my signature in the presence of two witnesses.

CHARLES F. SCHULTIS.
